Primary Examiner — Jennifer Rivard*Assistant Examiner* — Melanie Pellegrini(74) *Attorney, Agent, or Firm* — Archer & Greiner, P.C.(57) **CLAIM**

The ornamental design for gemstone jewelry, as shown and described.

DESCRIPTION

FIG. 1 is a top perspective view of gemstone jewelry showing my new design;

FIG. 2 is a top plan view thereof;

FIG. 3 is a bottom plan view thereof;

FIG. 4 is a front elevation view thereof, the rear elevation view being a mirror image thereof; and,

FIG. 5 is a right side elevation view thereof, the left side elevation view being a mirror image thereof.

The broken lines shown in the drawings represent unclaimed portions of the gemstone jewelry and form no part of the claimed invention.
